United States Patent

Des. 237,257
Patented Oct. 21, 1975

237,257

BOTTLE

Peter L. Schweizer, Liberty Center Ohio, assignor to Owens-Illinois, Inc.

Filed Feb. 11, 1974, Ser. No. 441,488

Term of patent 14 years

Int. Cl. D9—01

U.S. Cl. D9—142

FIG. 1

FIG. 2

FIG. 3

FIG. 1 is a front elevational view of a bottle showing my new design, the opposite side being a mirror image of the side shown;

FIG. 2 is an elevational view taken from the right of FIG. 1, the opposite side being a mirror image of the side shown; and

FIG. 3 is a top plan view thereof.

I claim:

The ornamental design for a bottle, substantially as shown and described.
